Primary Examiner — Natasha Vujcic*Assistant Examiner* — Gilbert B Ford(74) *Attorney, Agent, or Firm* — Revolution IP, PLLC(57) **CLAIM**

We claim the ornamental design for a microneedle pen tip, as shown and described.

DESCRIPTION

FIG. 1 is a front perspective view of a microneedle pen tip showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a bottom perspective view thereof.

The broken lines depict portions of the microneedle pen tip that form no part of the claimed design.
